UNITED STATES PATENT OFFICE.

CLAIBORNE CLINTON PIRTLE, OF DENISON, TEXAS.

HEATER.

1,304,596.

Specification of Letters Patent. Patented May 27, 1919.

Application filed July 22, 1918. Serial No. 246,181.

To all whom it may concern:

Be it known that I, CLAIBORNE C. PIRTLE, a citizen of the United States, and a resident of Denison, in the county of Grayson and State of Texas, have invented certain new and useful Improvements in Heaters, of which the following is a specification.

My invention is an improvement in heaters, and has for its object to provide a heater especially adapted for use with internal combustion engines, for the preliminary heating of the manifold before starting, to assist in starting in cold weather.

In the drawings:

15 Figure 1 is a front view of the improved heater in place;

Figs. 2 and 3 are sections on the lines 2—2 and 3—3, respectively, of Fig. 1, each view looking in the direction of the arrows adjacent to the line;

20 Fig. 4 is a section at right angles to Figs. 2 and 3;

Figs. 5, 6 and 7 are sections on the lines 5—5, 6—6 and 7—7, respectively, of Fig. 4, 25 each view looking in the direction of the arrows adjacent to the line.

The present embodiment of the invention is shown in connection with the manifold 1 of an internal combustion engine, the heater 30 being arranged at the connection 2 between the manifold and the carburetor (not shown). The heater comprises a casing 3 of substantially rectangular cross section, and having an opening in one wall and its 35 ends for receiving the connection 2, the edges of the walls of the heater casing 1 fitting closely about the connection to form a tight joint at the said connection.

Transversely of this heater casing near 40 the bottom and near the front or outer wall there is provided an auxiliary casing or firebox 4, the said casing or firebox 4 being adapted to contain a wick 5 of asbestos or the like.

45 Referring to Figs. 3, 4 and 5, it will be noticed that the side walls of the casing 4 are perforated, and the side and end walls are extended at the top of the auxiliary casing, as indicated at 6, to form a trough at 50 the top of the auxiliary casing for receiving gasoline when filling the wick with fuel. The casing is held in place by a bolt 7 which extends longitudinally of the auxiliary casing and transversely of the main casing 3, 55 the bolt passing through registering open-

ings in the casings and being engaged by a nut 8 at one end to hold the parts in place.

In order to permit the insertion of gasoline or other fuel in the auxiliary casing, an opening 9 is provided at one end of the main 60 casing just above the trough of the auxiliary casing, for the insertion of a spout, nozzle or the like, and this opening is adapted to be closed by a swinging door 10 which has a fingerpiece for manipulating the same as 65 shown in Figs. 1 and 2.

The casing 3 is provided near its bottom in its front wall with a series of air inlet openings 11 and in its top near the rear wall the casing is provided with a series of air 70 outlet openings 12, the said openings being arranged on each side of the connection 2. The casing is also provided with a series of inlet openings 13 in each side, the said series being arranged in inclined relation as shown, 75 and swinging doors 14 are provided for closing the openings, a door being arranged at each side of the main casing. Another air inlet 15 is provided just above the series 11, and a swinging door 16 is arranged between 80 the inlet 15 and the series 11, the said door being arranged to close either the inlet 15 or the series 11.

The casing 3 is secured to the manifold 1 by means of a clamp composed of L-shaped 85 sections 17. Each of these sections comprises a portion lapping alongside the heater casing and a portion extending upwardly and embracing the manifold. A bolt 18 is passed through the registering openings in 90 the ends of the vertical portions, and is engaged by a nut 19 to clamp the said portions on to the manifold. A second bolt 20 is passed through the front end of the horizontal portions of the clamp section, at the front 95 of the heater casing, and this bolt is engaged by a nut 21.

It will be understood that, if desired, the heater may be formed integral with the manifold. The form shown is especially 100 adapted for application to existing engines, since it may be clamped to the manifold. A baffle plate 22 is arranged above the auxiliary casing 4, this baffle plate extending from the front wall of the main casing to 105 near the rear wall, and the said plate has a series of openings, as shown.

In operation, the shutter or swinging door 10 is opened, and from a half to an ounce of gasoline or other liquid fuel is poured 110

into the trough formed by the extension 6 of the auxiliary casing. The fuel is poured in slowly, in order that it may be absorbed by the wick, and after it has been absorbed 5 the fuel is lighted. When burning, the fuel inlet opening is closed, and the draft openings are partially closed or left wide open, according to conditions. As soon as the fuel is burning properly, the hood is closed down, 10 and within from two to six minutes the manifold will be at a temperature that will convert the fuel into gas. It will be understood that the difference in the time required to heat the manifold depends upon the 15 weather. When the manifold is hot, the shutters of the draft openings are closed, which will at once extinguish the flame.

It will be understood that the attachment shown is especially adapted for existing engines, being capable of attachment to the manifold. It will be obvious that the casing might be cast with the manifold, forming an integral part thereof.

I claim:

- 25 1. A device of the character specified, comprising a casing adapted for connection with the manifold of an internal combustion engine, said casing having an auxiliary casing within the same, said auxiliary casing 30 containing a wick of asbestos or the like and having perforations in its walls, air inlet openings in the front and side walls of the casing near the auxiliary casing, shutters for controlling these openings, air outlet 35 openings in the top of the casing, a baffle

plate extending transversely of the casing above the auxiliary casing, said baffle plate having openings, the main casing having an opening in one side wall at one end of the auxiliary casing, and a shutter for closing 40 the said opening.

2. A device of the character specified, comprising a casing adapted for connection with the manifold of an internal combustion engine, said casing having an auxiliary cas- 45 ing within the same, said auxiliary casing containing a wick of asbestos or the like and having perforations in its walls, air inlet openings in the front and side walls of the casing near the auxiliary casing, shutters 50 for controlling these openings, air outlet openings in the top of the casing, and a baf- fle plate extending transversely of the casing above the auxiliary casing.

3. A device of the character specified com- 55 prising a casing, means for securing the cas- ing to the manifold of an internal combus- tion engine, an auxiliary casing held within the main casing and having perforated walls and adapted to contain a wick of asbestos or 60 the like, said main casing having inlet and outlet draft openings, means for controlling said openings, and having a fuel inlet open- ing above the auxiliary casing and at one end thereof, and a shutter for closing the 65 said openings.

CLAIBORNE CLINTON PIRTLE.
